UNITED STATES PATENT OFFICE.

NEWTON B. GOSSARD, OF ALTOONA, PENNSYLVANIA.

DESIGN FOR A SHIRT-FRONT.

SPECIFICATION forming part of Design No. 28,963, dated June 28, 1898.

Application filed July 20, 1897. Serial No. 645,266. Term of patent 3½ years.

To all whom it may concern:

Be it known that I, NEWTON B. GOSSARD, a citizen of the United States, residing at Altoona, in the county of Blair and State of Pennsylvania, have invented a new and original Design for a Shirt-Bosom, of which the following is a specification.

This invention relates to a new and original design for a shirt-bosom; and it has for its object to provide a design of this character which shall be both useful and ornamental.

The leading feature of the design resides in a flat truncated body of a general triangular form whose inclined edges converge from an intermediate point toward the truncated end, said body being provided at its wide end with an approximately semicircular reentrant cut, opposite straight parallel edges joining the convergent inclined edges, and with short inclined end edges connecting the straight parallel edges with the terminals of said semicircular cut.

In the drawings, Figure 1 is a plan view of a complete shirt-front having a bosom embodying the herein-described design. Fig. 2 is a view similar to Fig. 1, showing the reverse side of the bosom.

In the drawings the numeral 1 designates a flat truncated body of an irregular triangular

form and provided on each of its opposite sides 30 with a central longitudinal plait 2, extending from end to end thereof, and at its wide end with a semicircular loop 3, arranged centrally within an approximately semicircular reentrant cut 4. The inclined side edges 5 of the 35 body converge from an intermediate point toward the truncated end thereof, and said inclined edges 5 join with the opposite straight parallel edges 6. Short inclined end edges 7 connect the edges 6 with the terminals of the 40 semicircular cut 4.

The complete shirt-front is made up of a pair of bosoms 1, which have their adjacent parallel truncated ends spaced apart and connected by a pair of short oblong connecting- 45 pieces 8, which extend across the space between said ends.

What I claim is—

The design for a shirt-front herein shown and described. 50

In testimony that I claim the foregoing as my own I have hereto affixed my signature in the presence of two witnesses.

NEWTON B. GOSSARD.
